UNITED STATES PATENT OFFICE.

ALBERT RAY PETERSON, OF MINDEN, NEBRASKA.

DOOR OR GATE LATCH.

1,115,563.

Specification of Letters Patent.

Patented Nov. 3, 1914.

Application filed January 31, 1914. Serial No. 815,622.

To all whom it may concern:

Be it known that I, ALBERT R. PETERSON, a citizen of the United States, residing at Minden, in the county of Kearney and State 5 of Nebraska, have invented a new and useful Door or Gate Latch; and I do hereby declare the following to be a full, clear, and exact description of the invention, such as will enable others skilled in the art to which it 10 appertains to make and use the same.

This invention relates to a new and useful door or gate latch.

An object of the invention is to provide an improved latch, which may be applied 15 to either a laterally or vertically swinging door or gate, or to a sliding door or gate, the same being arranged or applied in a similar manner in all three instances.

In practical fields the details of construction 20 may necessitate alterations, falling within the scope of what is claimed.

The invention comprises further features and combination of parts, as hereinafter set forth, shown in the drawings and claimed.

25 In the drawings:—Figure 1 is a view in elevation showing the improved latch as applied to a laterally swinging gate. Fig. 2 is a detail perspective view, clearly showing the latch construction, and the means for 30 automatically locking the latch. Fig. 3 is a detail view showing a gravity latch locking plate. Fig. 4 is a view in elevation showing the latch applied to a vertically swinging gate.

35 Referring more particularly to the drawings, 1 designates a post, which may in some instances be a door frame. The latch 2 is provided with a slot 3 to receive the pivot bolt 4, on which the latch is pivoted, there 40 being a spring 5 to hold the latch so that the end 6 of the slots will always engage the pin 4. This spring 5 connects to the latch at 7, and to the gate or door at 8, and not only holds one end of the slot normally in 45 engagement with the bolt, but also holds the portion 9 of the latch normally in engagement with the abutment 10. A keeper arched strap 11 is bolted to the gate or movable member as at 12 and acts as a guide for 50 the latch end of the latch. The latch end of the latch is provided with a notch 14, which engages the notch or recess 15 of the latch plate 16, which is secured to the post 1, as at 17. As the gate or door is swung to a 55 closed position, the crotch of the notch 14 engages the inclined edge 18, raising the

latch, so as to cause the notches 14 and 15 to engage one another, thereby locking the gate or door. If the latch and gate are arranged so as to permit the gate to swing 60 in a reverse direction, the notch 14 slides upon the inclined edge 19 of the plate 16, so that the notches 14 and 15 will engage one another. If the gate or door is constructed to slide, then the inclined edge 20 65 of the latch will engage the notch 15, thereby raising the latch to permit the notches 14 and 15 to engage. If the gate or door is arranged to swing vertically, then the latch operates or falls in engagement with the 70 notch of the plate 16, as indicated in full and dotted lines in Fig. 4, thereby pushing the same rearwardly against the action of the spring 5, to permit the notches 14 and 15 to engage. Secured to the gate as at 22 75 is a handle 23, by which the gate may be manipulated. The rear end of the latch is constructed with a thumb piece 24, so that the latch may be tilted or pushed rearwardly, so as to render it possible to open 80 the gate.

It is evident that the structure shown in Figs. 1 and 2 may also be applied to a sliding gate.

The slot 3 is constructed with an offset re- 85 cess 3^a to receive the pivot pin 4 to hold the latch thrown backward.

When the gate is thrown to a closed position the latch will engage the inclined edges of the plate 16, and slide upwardly upon 90 the same so that said notches will coöperate. But before the notches 14 and 15 can engage, the latch throws the gravity latch locking plate from its path, and after the notches do engage, said latch locking plate 95 falls or returns to its normal position above the latch, thereby preventing the latch being tilted by an animal. This latch locking plate comprises two parts 25 and 26 hinged together at 27 the part 25 is pivoted at 28 100 to the fence post 1. The part 26 is hinged in such a manner, as shown in Fig. 3 as to only permit the same to swing in the recess 30 of the fence post, but not in the opposite direction. When it is desired to open the gate 105 the latch locking plate at one body is swung from the path of the latch, then the thumb piece 24 is depressed, so as to disengage said notches, after which the gate may be swung open. This same mode of operation is carried out in opening a sliding or vertically 110 tilting gate. It will be observed that in clos-

ing a swinging gate, the latch knocks the latch locking plate from its path. In closing a sliding gate the latch tilts the part 26 inwardly of the recess 30 of the post 1. In 5 closing a vertically tilting gate, the latch engages as shown in dotted lines with the latch locking plate, and is pushed rearwardly against the action of the spring 5, but as the nose of the latch comes in contact 10 with the tilting part 26, said part is thrown inwardly of the recess 30, thereby permitting the notches to coöperate.

The invention having been set forth, what is claimed as new and useful is:

15 In combination, a stationary member and a movable element, the stationary member having a recess in one face, a plate secured to the face in which said recess is formed and extending partially upwardly across the 20 recess, said plate having a notch, a second plate secured to the stationary member above the recess and provided with a pivoted device extending partially downwardly across the recess, said pivoted device being 25 designed to swing into said recess, a latch

mounted upon the movable member and having slideable and pivotal connections therewith, said slideable pivotal connections including an elongated slot having an offset recess, spring tensioning means for holding the latch so that the pivotal connection will engage the end of the slot opposite the offset recess, a keeper strap arching over the latch, said latch being provided with an inclined forward end and a notch, which is 30 designed to engage the notch of the first plate on the stationary member, said pivoted device constituting means to hold the notches of the latch and said first plate in coöperation, said pivoted device being adapted to 35 swing inwardly of the recess to permit said notches to coöperate.

In testimony whereof I have signed my name to this specification in the presence of two subscribing witnesses.

ALBERT RAY PETERSON.
